(57) **CLAIM**

We claim the ornamental design for a lighting device, as shown and described.

DESCRIPTION

FIG. 1 is a top view of the lighting device of the design.

FIG. 2 is a right side view of the lighting device of the design.

FIG. 3 is a bottom view of the lighting device of the design.

FIG. 4 is a left side view of the lighting device of the design.

FIG. 5 is a front view of the lighting device of the design.

FIG. 6 is a rear view of the lighting device of the design.

FIG. 7 is a rear perspective view of the lighting device of the design; and,

FIG. 8 is a front perspective view of the lighting device of the design.

Any broken line(s) shown are for illustrative purposes only and form no part of the claimed design.

The embodiments described herein are provided by way of explanation of the invention, which is not intended to be limited thereto. One of ordinary skill in the art may appreciate upon reading the present specification and viewing the present drawings that various modifications and variations of the shape and/or appearance of the presently claimed design may be made that would be evident from the one shown.
